M. A. FISCHER,
CLASP FOR NECKLACES AND THE LIKE,
APPLICATION FILED MAR. 17, 1921.

1,431,729.

Patented Oct. 10, 1922.

Milton A. Fischer Inventor
By his Attorney,
Joseph F. O'Brien

UNITED STATES PATENT OFFICE.

MILTON A. FISCHER, OF NEW YORK, N. Y.

CLASP FOR NECKLACES AND THE LIKE.

Application filed March 17, 1921. Serial No. 452,903.

To all whom it may concern:

Be it known that I, MILTON A. FISCHER, a citizen of the United States, and a resident of the borough of Manhattan, city, county, and State of New York, have invented certain new and useful Improvements in Clasps for Necklaces and the like, of which the following is a specification.

This invention relates to improvements in 10 clasps for necklaces and the like.

One of the objects of this invention is to produce a clasp for necklaces and the like which will be more simply, readily and easily operable to release and will have its 15 operating means more readily accessible to the user than is the case in other clasps.

Another object is to produce a clasp having a casing member which may, if desired, be suitably ornamented by the mounting of 20 stones therein or otherwise and which while bounded by symmetrical lines may be caused to lay flat on the neck of the wearer.

Another object of my invention is to produce a clasp device of the character described, in which the releasing movement is 25 effected by the manipulation of an operating sleeve which projects outwardly concentrically of the longitudinal axis of the casing beyond the insertion end thereof, and is provided with a finger piece which may, by 30 a pressure of the fingers exerted between said finger piece and the opposite end of the casing, cause a ready release of the insertion pin or rod by a movement of the sleeve toward the casing, thus providing a relatively large surface, to wit, the entire 35 length of the clasp for manipulation by the fingers of the user and producing a facile release, and also enabling all parts of the 40 casing to be closed against the admission of dust and dirt, etc.

With these and other objects in view, the 45 invention comprises the combination of members and arrangements of parts so combined as to co-act and cooperate with each other in the performance of the functions and the accomplishment of the results herein contemplated, and comprises in one of its 50 adaptations the species or preferred form illustrated in the accompanying drawings, in which:—

Fig. 1 is a longitudinal section of a clasp embodying my invention;

Fig. 2 is an edge view of the clasp shown 55 in Fig. 1; and

Fig. 3 is a section on the line 3—3 of Fig. 1 looking in the direction of the arrow.

Referring now to these drawings, and particularly to Figs. 1, 2 and 3, 1 indicates a casing having at one end an axial hole or 60 aperture 2 and provided with interiorly inclined faces 3 at opposite sides of the axis of the device, which faces are inclined toward the said axis and axial hole.

In the preferred form of my device the 65 casing is made rectangular in cross-section, closed at all sides and ends with exception of the axial hole 2 and has the inclined faces 3 at the opposite sides only, the top and bottom, preferably being formed flat and 70 the casing in order to present a symmetrical appearance is preferably substantially barrel-shaped or inclined inwardly toward its opposite ends. Obviously a casing of this 75 character may be ornamented in any suitable manner.

The clasp casing 1 has suitably connected thereto at its rear end a stationary chain-connecting member 10 also preferably disposed at the axis of the device and having 80 an eye 10^a.

Mounted and enclosed within said casing 1 to have longitudinal movement therein is a carrier 4 which is provided with a bore 5 coaxial with the hole 2 in the casing and 85 said carrier 4 is provided with transverse pockets 6 open at opposite sides to permit the riding of the balls 7 mounted in such pockets on the inclined faces 3 and the inclined faces 3 will cause such balls, during 90 the movement of the carrier toward the front end having the opening 2, to move toward and approach the axis of the device and project into the bore 5 of the said carrier so as to grip an object inserted into said 95 axial bore 5 of the carrier by a wedging between the surface of such object and the inclined faces. The movement of the carrier in the opposite direction will cause such balls to be moved out of wedging engagement 100 to release the object and permit free withdrawal thereof.

Suitable spring means for normally pressing the carrier 4 toward the front end of the casing having inclined faces is provided, and, 105 as shown, a compression spring 8 abuts at one end against the rear end of the carrier and at its opposite end against the end of the casing.

Connected to the carried and extending ax- 110

ially of the casing and through the hole 2 in the front end thereof is an operating sleeve 9 which is operable to move the carrier rearwardly. Said sleeve has a bore 5^a forming a continuation of the bore 5 of the carrier through which an insertion member having a chain connection is adapted to be moved. A movable chain connecting member 11 having a shank portion is adapted to be inserted or passed through the axial bores 5^a and 5 of the operating sleeve and carrier. Said shank is pointed at one end 11^a to permit ready insertion within the said bore and is provided at its opposite end with a chain link or eye 12.

It will be seen that when the rod 11 is moved within the casing, it will be engaged by the balls 7 which will by the compression spring 8 be caused to wedge between the inclined faces 3 of the casing and the surfaces of said rod 11, the balls in the carrier riding rearwardly during the insertion movement of the rod 11 to permit entrance thereof but being adapted to wedge as aforesaid and to prevent the withdrawal of the same unless the carrier be moved rearwardly to a wider portion of the casing.

In order to permit a more ready releasing of the rod and withdrawal of the same from the clasp-casing 1 so as to separate the ends of the chain, I preferably provide between the front or insertion end of the casing having the inclined faces and the chain-connecting eye 12 a finger-manipulated flange 13 adapted upon movement toward the casing to release the rod 11 and permit separation of the ends of the necklace. This is preferably accomplished by simultaneously squeezing the flange 13 and casing 1 between the fingers to press the flange inwardly toward the casing. This moves the balls to the wider part of the casing, releases the gripping engagement thereof with the movable, chain-connecting member and allows the necklace to which the clasp is attached to be removed from the neck of the wearer.

Having described my invention I claim:—
1. In combination, a casing having an axial hole at one end and an interior face inclined toward such hole; a carrier mounted to have longitudinal movement in said casing and provided with a bore in axial alignment with the hole in the end of the casing;

clutching elements carried by said carrier and adapted to ride upon said inclined face 55 and to project into the axial bore of the carrier; a movable chain-connecting member having a shank and connecting means for a chain, said shank being adapted to be inserted through the carrier bore; another 60 chain-connecting member having connecting means for a chain extending from the opposite end of the casing; a spring for normally forcing said carrier towards the interiorly inclined face and an operating sleeve connected with the carrier and extending forwardly of the insertion end of said clasp, whereby a squeezing between said forwardly extending sleeve and the opposite end of the casing may be effected by the fingers of the 70 user to release the insertion member.

2. In combination, a casing having an axial hole at one end and an interior face inclined toward such hole; a carrier mounted to have longitudinal movement in said 75 casing and provided with a bore in axial alignment with the hole in the end of the casing; clutching elements carried by said carrier and adapted to ride upon said inclined face and to project into the axial bore of the carrier; a movable chain-connecting member having a shank and connecting means for a chain, said shank being adapted to be inserted through the carrier bore; another chain-connecting member having connecting means for a chain 85 extending from the opposite end of the casing; a spring for normally forcing said carrier towards the interiorly inclined face and an operating sleeve connected with the carrier and extending concentrically in a forward direction through the insertion end of the casing outside the same and arranged concentrically of the movable chain-connecting member and a finger-manipulating 90 flange on the outer end of said sleeve movable between said bore and the chain connecting means of the connecting member to release said connecting member.

In witness whereof, I have signed my 100 name to the foregoing specification in the presence of two subscribing witnesses.

MILTON A. FISCHER.
